UNITED STATES PATENT OFFICE.

OTTO P. BAILER, OF MEMPHIS, TENNESSEE.

CLUSTER-BACK FOR JEWELRY.

1,343,246.

Specification of Letters Patent. Patented June 15, 1920.

Application filed May 1, 1919. Serial No. 293,926.

To all whom it may concern:

Be it known that I, OTTO P. BAILER, a citizen of the United States, and a resident of Memphis, in the county of Shelby and 5 State of Tennessee, have invented certain new and useful Improvements in Cluster-Backs for Jewelry, of which the following is a specification.

My invention relates to gem cluster setting and more particularly to the cluster back used in setting cluster tops in various mountings, and its application to such mountings.

Heretofore in the manufacture of cluster settings for jewels it has been a practice to form the back of a number of wires attached and soldered to the cluster top to represent a single stone, and being so soldered on the top it can only be used in that 10 way, that is the cluster back is not interchangeable or adaptable to different styles of mountings.

Among other expedients for cluster settings it has been proposed to solder the cluster back to a ring mounting on inside the 15 prongs of the ring.

In both of the illustrations given, solder is necessarily used, and this must be done by a skilled workman.

The principal object of my invention is to 20 do away with use of a necessity for solder, thus reducing the cost of manufacture.

Another object is to provide a cluster back that is interchangeable and can be quickly 25 applied or removed from any form of setting.

Another object is to provide a cluster back provided with facet elements to simulate the facets of a full gem.

A further object is to provide a reticulated basket-shaped cluster back having 30 portions designed to receive and hold enamel facets.

With these and other objects in view 35 my invention consists in certain novel features of construction, arrangement and combination of parts as will be hereinafter fully described and pointed out in the claims, reference being had to the accompanying 40 drawing, in which—

Figure 1 is a side elevation of a portion of a ring and its mounting showing application of my invention;

Fig. 2 is a top plan view of my improved 45 cluster back;

Fig. 3 is a side elevation of same; and

Fig. 4 is a side elevation of a cluster top adapted for combination with my cluster back.

In carrying out my invention I may use 60 gold, silver, platinum, or any other metal for the back, and I use a single seamless plate of the metal selected, and by any suitable means fashion it into a reticulated basket frame having the diamond 65 facet interstices A and A' or piercings as they are termed in the trade surrounded by the connecting strips B. The general shape of the back is that of a cone, the base of which is formed by the annular rim C, and 70 at the apex of the cone a circular perforation D is made.

The annular rim C is provided with one or more upwardly projecting lugs E, preferably of generally triangular shape with 75 the apex projecting upwardly, and the function of the lug is to fit into a similar shaped depression or socket in a cluster top, to prevent relative rotary movement of the two when combined. In Fig. 4 is shown 80 a cluster top F which may be conventional, except that it is provided with one or more notches or sockets f in the lower face at its edge.

The manner of utilizing my invention, the 85 cluster back having been provided with lug or lugs E and the cluster top F provided with the notch f, the back and top are united or interlocked by bringing the rim of the cluster back and the base of the cluster top 90 together with the lug E fitting and seated in the notch f; with the cluster back and cluster top so combined they are placed in the ring mount, with the rim C resting on the prongs G' of the ring G; the claws G² 95 are then upset or clenched over the cluster top at the various points of contact and the setting is then complete.

With the parts so constructed and arranged a very effective cluster setting is 100 produced, and the effect may be enhanced by filling the piercings or interstices A A' with transparent enamel to more clearly represent the back of the diamond. This may be done by filling the piercings with powdered enamel and fusing the same in an electric furnace.

The facet piercings A A', of course, are 105 designed to represent the facets of a diamond, and it is obvious that they may be 110

of different shapes than those illustrated in the present instance. In place of enamel in the facets, highly polished metal can be used.

5. The perforation or opening D at the lower end of the cluster back can be made any size desired, and enhances the simulation of the so-called "hole" at the back of real diamonds. The hole or culet may also be used 10 for cleaning the back of the cluster.

From the above it will be seen that I produce a cluster back that is made of a single piece of material and is seamless, one that is entirely solderless in either its make 15 up or application to other parts of the setting and one that is interchangeable and can be applied to other clusters now in use or to the clusters of other make without the aid of solder, and one with the use of which 20 the whole setting is held firmly in place and the parts held against relative rotary movement with respect to each other.

I claim:—

- 25 1. In gem settings of the type employing separable cluster tops and backings, a cluster-back comprising a reticulated basket and an integral annular rim at its upper end, and one or more lugs projecting upwardly from said rim.
- 30 2. In gem settings of the type employing separable cluster tops and backings, a cluster-back comprising a single sheet of seamless metal provided with piercings simulating gem facets and having a conical basket 35 shape including an annular rim at its upper end integral with the basket, and a perforation at its apex, and lugs projecting upwardly from said rim.
- 40 3. In gem settings of the type employing separable cluster top and backings, the combination with a cluster-back comprising a reticulated basket and an integral annular rim at its upper end, and one or more lugs projecting upwardly therefrom, of a cluster

top having mating notches in its base and 45 adapted for interlocking engagement with said lugs to prevent relative turning movement between the said cluster-back and cluster top.

4. In gem settings, a cluster setting comprising a ring mounting including shoulered prongs having claws at their outer ends, a cluster back comprising cone-shaped reticulated basket body and annular rim at 50 its upper end said rim seated on the shoulders of said prongs and within the claws of the same, lugs projecting from the upper face of said rim, a cluster top the base of which is provided with notches or recesses 55 engaging said lugs of the cluster back to hold said back and top against relative rotary movement, said cluster top also held to said back against said claws at the outer ends of the ring mount prongs.

5. In gem settings, a cluster back for 60 cluster settings comprising a cone-shaped open-work basket of metal, the piercings representing facets of a precious stone, and insertions in said piercings further simulating the effects of facets of such stone. 65

6. In gem settings, a cluster back for use 70 with a separable cluster top, comprising a basket-like body portion and an integral annular rim at its upper edge, said body portion provided with piercings insertions of 75 transparent enamel, and means for quick interchangeably interlocking said back with a cluster top.

7. As a new article of manufacture, a cluster back for gem settings consisting of a 80 seamless relatively thin sheet metal blank reticulated and dished to form a truncated cone-shape basket like body and an annular rim at its upper end, said rim carrying a nib or lug projecting axially therefrom and 85 adapted for interlocking and interchangeable engagement with a cluster top.

OTTO P. BAILER.
